UNITED STATES PATENT OFFICE.

WILLIAM KERR, OF PHILADELPHIA, PENNSYLVANIA, ASSIGNOR TO VAN DEVENTER & HORNE, OF NEW YORK, N. Y.

DESIGN FOR A CARPET.

SPECIFICATION forming part of Design No. 13,803, dated March 20, 1883.

Application filed February 15, 1883. Term of patent 3½ years.

To all whom it may concern:

Be it known that I, WILLIAM KERR, of Philadelphia, in the State of Pennsylvania, have invented a new Design for Carpets, of which the following is a specification.

5 This design relates to a pattern for carpets having Moorish appearance. The figures are set and heavy.

The stems of the leaflets are heavy and most 10 of them branch out angularly from each other, or are Y-shaped, as at *a a*. The leaflets are interspersed and contiguous, so as to form a pattern that extends with approximate uniformity all over the carpet, producing a mottled appearance, as shown. At intervals there are 15 quadrangular figures *b b*, formed of circles and leaflets, and placed in diagonal positions relatively to each other, or quincuncially.

The pattern, as a whole, is set heavy and angular in its appearance, and is adapted to 20 harmonize with some styles of architecture or furniture.

The pattern is repeated at intervals, as shown.

I claim as my invention—

The design of the figures in the carpet-pattern, consisting of the heavy stems branching angularly, the leaflets interspersed with an approximation to uniformity, and the quadrangular patterns, substantially as described and shown. 30

Signed by me this 9th day of February, A. D. 1883.

WILLIAM KERR.
